UNITED STATES PATENT OFFICE.

CHARLES N. F. KNAPE, OF WILKINSBURG, PENNSYLVANIA, ASSIGNOR TO WESTINGHOUSE ELECTRIC & MANUFACTURING COMPANY, A CORPORATION OF PENNSYLVANIA.

GUIDING TRUCK FOR LOCOMOTIVES.

Application filed August 8, 1922. Serial No. 580,408.

To all whom it may concern:

Be it known that I, CHARLES N. F. KNAPE, a citizen of the United States, and a resident of Wilkinsburg, in the county of Allegheny and State of Pennsylvania, have invented a new and useful Improvement in Guiding Trucks for Locomotives, of which the following is a specification.

My invention relates to guiding trucks for locomotives and particularly to means for effecting a relative transverse movement of the locomotive cab and trucks.

In the employment of locomotives having long wheel bases, flange wear at curves in the track is excessive, and the flanges of the wheels, as well as the heads of the rails, wear away rapidly.

Various methods have been proposed for eliminating this wear, including the provision of a plurality of articulated trucks beneath the cab body, and swing bolsters that permit the ends of the locomotive cab to move transversely of the truck frames on which they are supported, when the locomotive enters a curve. However, this procedure has not eliminated flange wear to the desired degree.

One of the objects of my invention is to provide an improved form of positive steering device so that the swiveled trucks of a railway vehicle will more readily follow the curvature of the rails.

Another object of my invention is the provision of positive steering mechanism for a railway vehicle, that is automatically operable when the vehicle encounters a curve.

Still another object of my invention is the provision of an improved form of mechanism for shifting the position of a railway vehicle body relative to its supporting structure.

As shown in the accompanying drawings,

Figure 1 is a view, partially in plan and partially in section, of a portion of a locomotive embodying my invention.

Fig. 2 is a view, partially in front elevation and partially in section, of the rear truck shown in Fig. 1.

Fig. 3 is a view, partially in rear elevation and partially in section, of the rear truck,

Fig. 4 is a view taken on the line IV—IV of Fig. 3, and

Fig. 5 is a detail view showing, in section,

the construction of the valves which I employ.

The invention is particularly applicable to electric locomotives that are provided with articulated trucks that are mounted for swiveling movement about the usual center pins. Fig. 1 shows the front and the rear trucks of the locomotive, with the intermediate portion broken away and the locomotive cab removed. A rear truck 6 and a front truck 7 have articulating movement with respect to intermediate trucks (not shown) and represent the trailing and leading trucks, respectively, of a locomotive, but they may be located intermediate the ends of the locomotive.

The truck 6 is provided with the usual transoms or cross-ties 8 that are supported upon truck side frames 9 and carry pins 11 that support heart-links 12, as shown more clearly in Figs. 1 and 2.

A swing-bolster 13 is supported between the lower ends of each pair of heart-links 12 by means of pins 14. The swing-bolster 13 is provided with a flanged upstanding portion 15 that serves as a support for a centering plate 16 that is secured to a member 17 on the underside of a cab (not shown). A pin 18 holds the centering plate 16 in place upon the bolster 13 and such plate permits of swivel movement by the truck 6. By reason of the link structure above described, the swing bolster 13 and the cab body supported thereby may move transversely of the truck 6, about the pivot points 11 and 14, in the manner common to swing bolsters of this character.

A cylinder 19 is secured to one of the transoms 8 and is provided with two pistons 21 and 22 that have stems 23 and 24, respectively, which slide in cross-heads 25 and 26 that are slidably supported within the cylinder 19. Air may be admitted to the cylinder through either of the admission ports 27 or 28, as will be hereinafter explained.

A lever 29 extends upwardly into the cylinder 19, between the cross-heads 25 and 26, and is secured at its lower end to a shaft 31. The shaft 31 is supported in bearings 32 and 33 that are formed in the lower portions of the transoms 8. A sleeve 35 is secured to the shaft 31 and is provided with teeth 36 that engage the teeth of a rack portion 37

formed upon the underside of the swing bolster 13, so that when rotative movement is imparted to the shaft 31, the swing bolster and the truck will be relatively moved transversely of the truck frame, about the pivot pins 14 and 11, as above explained.

The oscillation of the shaft 31 is effected by means of the pistons 21 and 22. When, for instance, the piston 21 is moved inwardly by the admission of fluid pressure through the port 27, the inner end of the stem 23 is brought into engagement with the lever 29 to effect a rotative movement of the shaft 31 and the toothed sleeve member 35 carried thereby. When the pressure is relieved, a coil spring 38 will return the piston 21 to its retracted position. The operation of the piston 22 to cause movement of the shaft 31 in the opposite direction is effected in a similar manner, by admission of fluid pressure through the port 28.

The front truck 7 is provided with a swing bolster 41 that is supported upon transoms 42 by heart links 43, and has swivel connection with a member 44 that is secured to the underside of the cab, through a centering plate (not shown) that is supported by the bolster 41. This portion of the front truck 7 is substantially the same in construction as the corresponding portion of the truck 6, above described.

One of the transoms 42 carries an electrical switch member 45 and two co-operating switch members 46 and 47, that are supported by the cab body (not shown). The switch member 45 is connected to a source of energy, such, for example, as a battery 48. Should the truck 7 enter a right-hand curve, it will swivel about the center pin 40 (not shown), owing to the tendency of the cab to continue in a straight line, and the switch member 45 will move into engagement with the contact member 47, thus completing a circuit through a conductor 49, a coil 51, and the battery 48. When the truck 7 enters a left hand curve, the switch member 45 will be carried into engagement with the contact member 46 and complete a circuit through a conductor 52, a coil 53 and the battery 48.

The coils 51 and 53 are each provided with a core 54 that has a rack 55 formed thereon and is normally biased to retracted position by a spring 56.

The coil 51 serves to control the movements of a valve 57 through a gear wheel 58 that moves with the rack 55. The valve 57 is provided with a port 59 that communicates with a fluid-pressure reservoir 61, a port 62 that has communication, through a flexible pipe 63, with the admission port 28 of the cylinder 19, and with an exhaust port 64.

The coil 53 and its core 54 control a valve 65 that has a port 66 which leads to the

reservoir 61, a port 67 that has communication with the admission port 27 of the cylinder 19, and with an exhaust port 68. When the ports are in the position indicated in Fig. 1, and the front truck 7 enters a right hand curve, the coil 51 will be energized, as above explained, to attract the core 54 against the tension of the spring 56, thus operating the valve to effect communication between the reservoir 61 and the admission port 28 of the cylinder 19 and causing the piston 22 to move inwardly into engagement with the lever 29 and effecting a swinging movement of the bolster 13. This movement, as above explained, will carry the rear end of the body transversely of the truck 6 and reduce the tendency of the body to maintain the trucks 6 and 7 in alinement, thus permitting the trucks to more readily follow the curvature of the track. When the locomotive leaves the curve, the circuit through the coil 51 will be broken, by reason of the switch parts assuming the positions illustrated in Fig. 1 and the spring 56 will return the rack 55 to retracted position, thus bringing the valve parts to the position illustrated in Fig. 5, wherein the cylinder 19 may exhaust to the atmosphere and the piston 22 return, by the action of its spring, to the position shown in Fig. 3.

Should the locomotive enter a left-hand curve, the circuit through the coil 53 will be closed and an operation similar to that above described effected, through operation of the valve 65.

Should it be desired to apply the invention to a double-end locomotive, that is, one designed to operate in either direction, control apparatus like that carried by the front truck may be applied also to the rear truck 105 and a guiding cylinder may be applied to the front truck. Furthermore, a guiding force may be applied at both ends simultaneously.

Various other modifications in detail and general arrangement may be made without departing from the spirit and scope of the invention as defined in the accompanying claims.

I claim as my invention:

1. The combination with a locomotive cab and trucks for carrying the cab, of a swing bolster supported upon one of the trucks, means for supporting the cab upon the bolster, and means for automatically applying an extraneous force to the swing bolster when entering a curve in the track, for effecting movement of the bolster in a transverse direction.

2. The combination with a locomotive cab and trucks for carrying the cab, of a swing bolster supported upon one of the trucks, means for supporting the cab upon the bolster, and means for automatically applying an extraneous force to the swing

- bolster when entering a curve in the track, for effecting movement of the bolster in a transverse direction, and for eliminating the said force when the locomotive leaves the 5 curve.
3. The combination with a locomotive cab and trucks for carrying the cab, of a swing bolster supported upon one of the trucks, means for supporting the cab upon 10 the bolster, an air cylinder and piston for controlling the movements of the swing bolster, and means automatically actuated by swivel movements of the other truck for controlling the movements of the piston.
- 15 4. The combination with a locomotive cab and trucks for carrying the cab, of a swing bolster supported upon one of the trucks, means for supporting the cab upon the bolster, an air cylinder and piston for 20 controlling the movements of the swing bolster, and means automatically actuated upon swivel movements by one of the trucks for effecting movements of the piston.
5. The combination with a locomotive 25 cab and trucks for carrying the cab, of a swing bolster supported upon one of the trucks, means for supporting the cab upon the bolster, an air cylinder and piston for controlling the movements of the swing 30 bolster, an electromagnetically-operated valve for controlling the admission of fluid pressure to each end of the said cylinder, and means carried by the other truck for selectively controlling the circuits through 35 the said electromagnetic valves.
6. The combination with a locomotive cab, of a swing bolster for supporting the cab, a rack carried by the bolster, a truck frame, a gear wheel supported in the truck 40 frame and meshing with the rack, and means for imparting rotative movement to the gear wheel.
7. The combination with a locomotive 45 cab, of a swing bolster for supporting the cab, a rack carried by the bolster to effect a transverse movement of the bolster, a truck frame, a gear wheel supported in the truck frame and meshing with the rack, and means for imparting rotative movement to 50 the gear wheel.
8. The combination with a locomotive cab, of a swing bolster for supporting the cab, a rack carried by the bolster, a truck frame, a gear wheel supported in the truck
- frame and meshing with the rack, and a 55 fluid-pressure cylinder and piston for imparting rotative movement to the gear wheel.
9. The combination with a locomotive cab, of a swing bolster for supporting the 60 cab, a rack carried by the bolster, a truck frame, a gear wheel supported in the truck frame and meshing with the rack, a fluid-pressure cylinder and piston for imparting 65 rotative movement to the gear wheel, and means controlled by the movements of the cab with respect to its trucks for controlling the admission of fluid to the cylinder.
10. The combination with a locomotive cab, of a swing bolster, a truck for supporting the swing bolster, two interengaging members carried by the bolster and the truck respectively, and means for automatically effecting movement of one of said 70 interengaging members when the locomotive enters a curve.
11. The combination with a locomotive cab and trucks for supporting the same, the cab being transversely movable with respect to one of the trucks, of means for applying a force to effect a transverse 80 movement of the cab with respect to the said truck.
12. The combination with a pair of trucks, of a cab supported thereupon for 85 movement transversely of one of the trucks and means automatically operable when the locomotive enters a curve, for effecting said relative movement.
13. The combination with a locomotive 90 cab, of a truck for supporting the cab, inter-engaging members carried by the cab and the truck respectively, and means for applying a force to one of the said inter-engaging members to effect a transverse 95 movement by the cab with respect to the truck.
14. The combination with a locomotive cab and trucks for carrying the same, of means for automatically applying an ex- 100 traneous force to effect relative transverse movement of the cab and one of the trucks when the locomotive enters a curve.
- In testimony whereof, I have hereunto 105 subscribed my name this 15th day of July 1922.

CHARLES N. F. KNAPE.
